Primary Examiner — Cathron Brooks*Assistant Examiner* — Melanie Pellegrini(74) *Attorney, Agent, or Firm* — Venjuris P.C.(57) **CLAIM**

The ornamental design for an earring, as shown and described.

DESCRIPTION

FIG. 1 is a perspective view of an earring;

FIG. 2 is a front view of the earring;

FIG. 3 is a rear view of the earring;

FIG. 4 is a bottom view of the earring;

FIG. 5 is a top view of the earring;

FIG. 6 is a side view of the earring; and,

FIG. 7 is an alternate side view of the earring.

The broken lines shown in the drawings illustrate portions of the earring that form no part of the claimed design.
